UNITED STATES PATENT OFFICE.

WILLIAM D. SARGENT, OF CHICAGO, ILLINOIS.

BRAKE-SHOE.

SPECIFICATION forming part of Letters Patent No. 555,975, dated March 10, 1896.

Application filed December 13, 1895. Serial No. 572,057. (No model.)

To all whom it may concern:

Be it known that I, WILLIAM D. SARGENT, a citizen of the United States, residing at Chicago, in the county of Cook and State of Illinois, have invented certain new and useful Improvements in Brake-Shoes, of which the following is a full, clear, and exact description, reference being had to the accompanying drawings, forming a part of this specification.

This invention relates to the class of brake-shoes known in the art as "dressing" brake-shoes, because, in addition to their function of brakes, they serve the purpose of dressing the entire tread and flange of car-wheels in proportion to the wear on said wheels resulting from contact with the rails. This class of brake-shoes is exemplified in Letters Patent of the United States No. 523,084, granted to me July 17, 1894, upon which my present invention is more especially designed as an improvement.

The primary object of this invention is a brake-shoe which will not only dress car-wheels proportionately to the wear thereof, due to contact with the rails, so as to maintain the tread and flange of the wheels in uniform and proper condition at all times during their lives, but will also possess the maximum degree of longevity in service without detriment to the strength or braking quality of the shoe.

A further object is to provide a brake-shoe with a wearing-surface that shall be practically continuous over the tread and flange of a car-wheel, which will dress with maximum effect those portions of the wheel which do not contact with the rail, and which will dress those portions of the wheel that are worn by contact with the rail with proportionate effect and which will yet have a composite metallic wearing-surface, a portion of which is directed to afford a braking effect, while the other portion serves to retard the wear of the shoe.

Another object of the invention is a brake-shoe having integral hard and soft or composite metallic wearing-surfaces, which shall possess in the maximum an exceptional degree of strength, durability, and effectiveness.

These and such other objects as may hereinafter appear are attained by the device illustrated in the accompanying drawings, in which—

Figure 1 is a perspective view of a brake-shoe provided with alternate chilled parts and openings. Fig. 2 is a cross-sectional view of the brake-shoe shown in Fig. 1, taken through an opening. Fig. 3 is a perspective view showing a brake-shoe provided with chilled surfaces and without openings. Fig. 4 is a transverse sectional view of the shoe shown in Fig. 3. Fig. 5 is a perspective view of an ordinary flat brake-shoe. Fig. 6 is a cross-sectional view of a flat brake-shoe, showing a flange on the back thereof; and Fig. 7 is a diagrammatic view illustrating the wear upon a wheel and the position of the chilled parts in the brake-shoe with relation to the wear on the wheel.

In all of the figures, A designates the body portion of the brake-shoe, and B the chilled parts thereof. These chilled parts may be variously disposed, and in Fig. 1 I have shown them arranged alternately with openings C, one or more of which may be provided as desired. In this case the chilled parts extend through all that portion of the shoe between the openings, as clearly shown in Fig. 1.

In Fig. 3 I have shown a number of chilled parts with narrow webs D separating said parts, and in Fig. 5 the webs separating the chilled parts are wider than those shown in Fig. 3. These chilled parts may be made in many ways, but a common way is to subject parts of the shoe to the action of a cold piece of metal in the process of casting. The chilled parts may be of any desired configuration and size, and it will be understood by those skilled in the art, as well as by others, that the number and size, as well as the location and arrangement of the chilled parts with relation to the other parts of the brake-shoe, will vary under different conditions, but the chilled parts are arranged in such a position with relation to the other parts of the brake-shoe that they will be located opposite to that portion of the wheel which is worn by contact with the rail, and those portions of the wheel which do not contact with the rail, and therefore are not worn, will be dressed by the soft parts of the brake-shoe around the chilled parts thereof with maximum effect.

In Fig. 7 I have shown the preferred location of the chilled parts with relation to the wear on the wheel. In actual use it will be

- found that the chilled parts of the brake-shoe wear more or less, but they do not have the dressing effect upon the wheel that is afforded by the other parts of the brake-shoe.
- 5 While the soft parts of the brake-shoe wear the wheel by reason of the grinding action afforded by the particles rubbed off of the shoe the chilled parts form polished surfaces and do not, to any material extent, dress the portion 10 of the wheel with which they come in contact. The chilled parts merge into the soft parts of the shoe gradually, and the corners thereof are rounded, as at F, whereby the dressing-face of the shoe is gradually enlarged 15 on either side of the line where the wheel is worn the most by the rail.
- The foregoing will be clearly understood by referring to the diagrammatic view, Fig. 7, in which G represents the car-wheel; H, the 20 rail; I, a portion of the brake-shoe; J, the original outline of the car-wheel, and K the outline showing the ordinary wear upon a car-wheel by the rail to which a dressing brake-shoe has not been applied in service.
- 25 That portion of the wheel-tread between the lines a a' represents the area of maximum and practically uniform wear of the rail upon the wheel-tread.
- That portion of the wheel-tread between 30 the lines a and b and a' and b' represents the area of proportional wear of the rail upon the tread, the minimum wear being at about the lines b b' . That portion of the tread and flange between the lines b c and b' c' represents 35 the area of no wear upon the wheel by the rail, because these portions of the wheel never come in contact with the rail. It is therefore desirable to dress with maximum wearing effect substantially that portion of 40 the wheel tread and flange included between the lines b c and b' c' , to dress with minimum wearing effect that portion of the wheel-tread between the lines a and a' , and to dress with a proportionate effect from the maximum to 45 the minimum that portion of the wheel tread and flange between the lines a b and a' b' . That portion of the shoe indicated by the letter d is intended to illustrate the merging 50 of the chilled portion of the brake-shoe into the soft or unchilled portion thereof, and while I have shown in this view and in the other views a comparatively sharp line of demarcation between the chilled and unchilled or soft portions of the shoe, in practice no 55 such line does or can exist, as the effect of the chill will extend, in a rapidly-lessening degree, from the desired outlines of the chilled portion into the soft portion, so that the wearing-surface of my brake-shoe, in point of fact, 60 is of composite metal of three degrees of hardness, the hardest being over the area of maximum wear, the softest being over the area of minimum wear and the intermediate being over the area of proportionate wear of the rail 65 upon the wheel.

I am aware that there are many different constructions in the art which propose or at-

tempt to provide for the uniform dressing of wheels aside from my patented invention hereinbefore referred to, but so far as I am aware it is broadly new to provide chilled parts in a brake-shoe which are disposed so that they will contact with or be located opposite to that portion of the wheel which received the greatest wear by contact with the rail.

The use of chilled parts in the manner I have described will provide a brake-shoe of great strength and durability.

In Figs. 4 and 6 of the drawings I have shown the rib E, which is provided on the back of the brake-shoe for attachment to the brake-head. I have also shown two different forms of brake-shoes in these drawings which appear to be sufficient for the purpose of fully disclosing the invention, but it will be understood, of course, that the improvements may be embodied in brake-shoes of any kind not inconsistent with the purposes of the invention.

It will be noted in Figs. 2 and 6 more especially that the contour of the wearing-surface of my shoe does not coincide exactly with that of the wheel tread and flange, or, in other words, that the chilled portion practically spans between the tread and flange of the brake-shoe over the areas of maximum and proportionate wear and does not make contact therewith. This condition, however, to the fullest extent exists only when the shoe is first applied to the wheel, the length of span gradually lessening as the shoe wears, until finally the contour of the shoe and wheel will actually correspond. This feature is important in order to avoid detriment to the full effectiveness of the brake-shoes when first applied, which might result from carelessness or the exigencies of chilling, when the chilled portion might otherwise serve for some time to prevent the application of the full wearing-surface of the shoe to the wheels when first applied, and consequently prevent the maximum braking effect of the shoe being brought into play.

I am aware that changes and variations in the form and proportion of the different parts of my improved brake-shoe may be made without departing from the spirit or sacrificing the advantages of the invention, and I would therefore have it distinctly understood that I reserve to myself the right to make all such changes as fall within the spirit and scope of the invention.

Having thus fully described my invention, what I claim, and desire to secure by Letters Patent, is—

1. A brake-shoe composed of cast metal having chilled parts in its wearing-surface so disposed as to contact only with that portion of the wheel which contacts with the rail, substantially as described.

2. A cast-metal brake-shoe having a composite integral wearing-face composed of unchilled cast metal, chilled cast metal and par-

tially-chilled cast metal, the chilled portion being located opposite the area of maximum wear of a rail upon a car-wheel, substantially as described.

- 5 3. A cast-metal brake-shoe having continuous wearing-surfaces to bear upon those portions of the wheel which do not make contact with the rail, that portion of the shoe between such continuous wearing-surfaces being 10 chilled so as to leave a substantially uniform wearing-surface of chilled metal over the area of maximum wear of the rail upon the wheel, approximately from a to a' , and gradually decreasing wearing-surfaces of chilled metal 15 between said uniform chilled portion and the said continuous wearing-surfaces, approximately from a to b and a' to b' , substantially as described.
4. A brake-shoe composed of soft metal 20 having chilled parts located in the wearing-

surface of said shoe opposite that portion of the wheel which contacts with the rail, said chilled parts being substantially uniform opposite the area of maximum wear of the wheel and gradually reduced from said uniform 25 portion at each side to approximately a point where the wear of the rail upon the wheel ceases, substantially as described.

5. As a new article of manufacture, a brake-shoe having parts of its wearing-surface 30 chilled opposite that portion of the wheel which contacts with the rail, said chilled portion being adapted and arranged to span the area of the wheel worn by contact with the rail when first applied to the wheel, substantially as described. 35
